AIR CONDITIONING UNIT FOR MOTOR VEHICLES

Joseph M. North, Arnold, Kans.

Application January 11, 1954, Serial No. 28,436

Term of patent 14 years

(Cl. D62—4)

To all whom it may concern:

Be it known that I, Joseph M. North, a citizen of the United States, residing at Arnold, State of Kansas, have invented a new, original, and ornamental Design for an Air Conditioning Unit for Motor Vehicles, of which the following is a specification, reference being had to the accompanying drawing, forming part thereof, in which:

Fig. 1 is a front perspective view of an air conditioning unit for motor vehicles embodying my new design; and

Fig. 2 is a rear perspective view thereof.

I claim:

The ornamental design for an air conditioning unit for motor vehicles, substantially as shown.
